FISH LURE

George Fofrich, 1802 E. Manhattan Blvd., Toledo, Ohio

Filed Mar. 28, 1961, Ser. No. 64,524

Term of patent 14 years

(Cl. D31—4)

FIG. 1.

FIG. 2.

FIG. 5

FIG. 3.

FIG. 4.

I claim:

The ornamental design for a fish lure, as shown.
